UNITED STATES PATENT OFFICE.

TITO GIARDI, OF ROME, ITALY.

AUTOMATIC NEWSPAPER-DISTRIBUTER.

1,277,568.

Specification of Letters Patent. Patented Sept. 3, 1918.

Application filed December 6, 1915. Serial No. 65,241.

To all whom it may concern:

Be it known that I, TITO GIARDI, of Viale della Regina No. 86, Rome, Italy, have invented certain new and useful Improvements in Automatic Newspaper-Distributors; and I do hereby declare the following to be a full, clear, and exact description of the same.

The object of the present invention is to provide a machine for newspaper distribution, which is simple and efficient. The invention consists of the construction, combination and arrangement of parts as herein illustrated, described and claimed.

15 In the accompanying drawings, forming part hereof, is illustrated a form of embodiment of the invention, in which drawings similar reference characters designate corresponding parts, and in which:

20 Figure 1 is a vertical section, partly broken away, taken approximately on line A—B of Fig. 2;

Fig. 2 is a horizontal section;

Fig. 3 is a fragmentary detail in perspective showing on enlarged scale the parts numbered 6 to 9 on the Fig. 1;

Fig. 4 is a diagrammatic view illustrating the shifting of the newspapers with a run of a $\frac{1}{2}$ of the side;

30 Fig. 5 is a perspective view of the apparatus, with part of the walls and the illustration of newspapers omitted for the sake of clearness;

Fig. 6 is a fragmentary detail in longitudinal section of the coin control device;

Fig. 7 is a fragmentary detail in vertical section taken approximately on line E—F of Fig. 6; and,

Fig. 8 is a fragmentary detail in perspective of the coin actuating means employed and which may be of any form.

Newspapers O, magazines, or the like, are introduced, placed over each other regularly, into a casing 1, above a base-plate 2. This 45 plate may be flat or a little convex toward its forward edge and, in its turn, is supported by one of the shelves of the casing on bearing plate 1¹ pivoted at the ends of its front edge on the sides of the casing 1.

50 The said plates and consequently the newspapers, or such-like, are arranged either horizontally (Fig. 1 upper part), or inclined upward for newspapers or thin or light printed sheets (Fig. 1 lower part), or 55 inclined downward for heavy and stiff magazines.

Two vertical uprights 3 connected with each other as a frame by horizontal cross pieces 15—15¹, are each formed with guideways. The frame is supported on slides 4 movably disposed in suitable guides 4¹ arranged parallel to the base-plate. When the base-plate 2 is to be arranged at an angle, the uprights 3, by means of suitable connections with slides 4, may be kept vertical, as shown in the drawings. The slides and uprights are moved from outside by any suitable means, such as knob 12 in the front, connected with them.

60 The function of the knob 12, and its connected parts, is to actuate the uprights 3 backward, and at the same time to lift a counterweight 13, shown in Fig. 5, connected with the uprights 3 and arranged to actuate the uprights 3 forward, and hence 65 to effect the displacement of one newspaper as described below.

70 A connection between the knob 12 and the counterweight 13 is made by means of a flexible member 14 disposed around small 80 pulleys 16, the intermediate pulleys being connected with the metallic plate 1¹, while those at the ends are fixed to the casing 1. Between the handle 12 and the uprights, for instance, at 12¹ (Fig. 5), or at any suitable 85 point, a connecting device may be inserted, being operated by the introducing of the coin. The flexible member 14 passes under the cross bar 15 and around the pulley 16 on the plates 2 and is connected at its end 90 to the cross bar 15.

95 The counterweight 13 is connected with a small air pump 13¹ acting as a pneumatic brake or dash-pot when actuated downward, said pump being provided with a very small 95 air outlet 13², which can be adjusted to regulate the speed of movement of the displacement of the newspaper after starting the apparatus. Starting the machine on account of the compression of the air in the brake-pump may take place with greater speed i.e., with some abruptness.

100 This arrangement thus facilitates, through inertia or sluggishness, the separation of a single newspaper from those underneath.— 105 the inclination upward of the newspapers (Fig. 1 lower part) also contributing to the same end. Disposed in the guideways of the uprights 3 are the ends of a light rod 5 adapted to run freely downward by its own 110 weight. Carried by the rod 5 is a light block 6, rockably secured by means of pivots

6^a, on ears 5¹ carried on the underside of bar 5. On the forward movement of the bar 5, the block 6 assumes the position shown in Fig. 1, lower part, and in its backward movement the position shown in Fig. 1, upper part, by friction with the papers O. The block 6 has underneath its and toward its front part, a plate 7 secured by screws so that it is easily removable. A plurality of 10 small metallic points 7^a are carried on the lower face of the plate 7 of a length according to the thickness of the separate newspapers. The points 7^a may be arranged either perpendicular or inclined forward 15 and downward, with respect to the surface of the newspaper in which they are to stick. Over the rod 5 is fixed, a metallic plate 5² (Figs. 2 and 3) to increase or regulate the load on the points 7^a.

20 The block 6 is further provided on its front part with a curved metallic plate 8 arranged to strike the upper surface of the newspaper O and to limit the rocking of the block 6 to prevent its turning over. Carried by the plate 8 is a pair of fingers 9, formed preferably of wire and pivotally held, which serve to push forward the newspapers previously displaced from the pile by the points 7^a when the block 6 is actuated 25 forward. For this purpose, the ends of the fingers are bent downward, or the fingers 9 may even be substituted by the plate 8 properly prolonged, when the thickness of 30 the newspaper folds is trifling.

35 At the start of the forward movement of the two uprights 3 determined by the weight 13, the block 6, rocking by frictional contact with the papers O, forces its points 7^a into the paper for the entire length of said 40 points and until plate 7 comes into contact with the paper and stops their penetration, and then the block pushes one newspaper forward for about half of its length. Then, being forced back under the movement of 45 the handle 12, the block 6 is rocked, also by friction, its points are retracted and, leaving the first newspaper where it is, returns to its original position, only sinking, together with its rod 5, to the extent of the 50 thickness of the newspaper displaced.

The counterweight 13 is released at the end of the run of the block 6, by releasing the handle or by the action of a coin introduced into the coin control herein described, 55 if such device is used. When movement of the uprights 3 again takes place, the block 6 begins the displacement of a second newspaper, which, either by itself or by the effect of the two fingers 9, forces the first 60 newspaper forward until it falls into the hopper 10 and comes out at the front of the case through the slot 11.

The weight and bending down of each newspaper previously displaced operate so 65 as to bend down in its turn the following

one, as soon as it has been shifted thus facilitating its movement toward the hopper. With this aim also the action of two successive newspapers may be utilized, limiting the rocking of the block 6, so that the plate 70 8 and fingers 9 push forward one newspaper each simultaneously. This may also be done without the bending of the previous newspaper, displacing each newspaper or magazine for more than half its width until it 75 drops over into the hopper.

The application of either system as also the horizontal or the inclined position of the heap of newspapers which has already 80 been spoken of corresponds to the various conditions of weight, thickness, and stiffness of the separate newspapers. The rockable block 6 may also be substituted by a piece stationary with respect to the rod 5; that is to say, the rocking of said block 6 is 85 not necessary when the points are inclined at least about forty-five degrees so that while they stick into the paper during forward movement, they leave the paper, on account of their inclination, during backward movement, producing only a slight line or mark on the paper itself.

The casing 1 may comprise a series of compartments placed over each other, or even several series of such compartments 95 conveniently grouped and adapted to stand against the wall of an edifice, or to stand isolated like a kiosk.

Having thus described my invention, what I claim as new and desire to secure by Letters-Patent is:

1. In a device of the character described the combination comprising a casing, a base member in the casing arranged to remain inclined and to support, a pile of newspapers or like, a pair of grooved members arranged on each side of the base member, a frame supported to have reciprocating movement on the grooved members parallel to the base, guideways on the vertical uprights of said frame, a light horizontal rod adapted to slide freely vertically in the guideways of the said uprights, paper engaging means carried by said rod adapted to engage the paper only in one direction and means arranged to move from outside the said frame for a portion of the length of the newspapers or like.

2. In a device of the character described the combination comprising a base member 120 arranged to remain either horizontal or inclined and to support a pile of newspapers or like, a pair of grooved members arranged on each side of the base member, a frame supported to have sliding movement on the 125 grooved members parallel to the base, guideways on the vertical uprights of said frame, a light horizontal rod adapted to slide freely vertically in the guideways of the said uprights, paper engaging means carried by 130

said rod adapted to engage the paper only in one direction, means for moving the frame only in the backward direction, a counterweight arranged to return the said frame in its initial position and an air pump adapted to be operated by said counterweight so that the downward movement of said counterweight and the speed of the displacement of the newspapers is regulated.

3. In a device of the character described, the combination comprising a casing, a base member in the casing arranged to support a pile of newspapers, a pair of grooved members arranged on each side of the base member, a frame supported to have sliding movement on the grooved members, sheet engaging means carried by the frame, a handle disposed outside of the casing, a flexible member connecting the handle and the frame arranged to move same in one direction, and means for returning the frame to its initial position.

4. In a device of the character described, the combination comprising a casing, a base member in the casing arranged to support a pile of newspapers, a pair of grooved members arranged on each side of the base member, a frame supported to have sliding movement on the grooved members, sheet engaging means carried by the frame, means for moving the frame in one direction, a flexible member connected to the frame, a counterweight on the flexible member, and a pump arranged to be operated by the counterweight so that movement of the frame in one direction is retarded.

In testimony whereof I have signed my name to this specification in presence of two subscribing witnesses.

TITO GIARDI.
